UNITED STATES PATENT OFFICE.

BENJAMIN LOUIS TOQUET, OF WESTPORT, CONNECTICUT.

APPARATUS FOR CATCHING AND DELIVERING MAIL-BAGS AND THE LIKE.

No. 885,889.

Specification of Letters Patent.

Patented April 28, 1908.

Application filed February 10, 1908. Serial No. 415,158.

To all whom it may concern:

Be it known that I, BENJAMIN LOUIS TOQUET, a citizen of the United States of America, residing at Westport, in the county of Fairfield and State of Connecticut, have invented certain new and useful Improvements in Apparatus for Catching and Delivering Mail-Bags and the Like, of which the following is a specification.

10. My invention relates to apparatus for catching and delivering mail bags and the like and consists in the improvements set forth hereinafter.

The particular object of my invention particularly with relation to mail bag catchers, is not only to secure the advantages of a freely swinging catching arm but also to provide means in connection therewith for shortening the radial length of the arm after 20 the delivery of the bag so as to prevent the bag from swinging out against the passing train under the influence of centrifugal force as the arm continues to rotate. In connection herewith I provide also a novel catching 25 device for the arm.

In the accompanying drawings in which an apparatus embodying my invention is shown, Figure 1 is an elevation of a mail bag receiving and delivering platform, provided with 30 my device; Figs. 2 and 3 are respectively plan and side elevations of the catching arm drawn to a larger scale, and Fig. 4 is a broken side elevation of the catch in operation.

Referring to the drawings, it will be seen 35 that my improved device in the form illustrated, comprises a column 1 supported by a base 2 which may conveniently be attached to elongated track ties for the sake of additional rigidity. A cam 3 is firmly secured on 40 the column at a suitable height for the purpose hereinafter explained. The swinging arm 4, provided at its outer extremity with a catching device, slides freely through a slotted offset 5 on the carrier sleeve 6 which 45 is loosely mounted on the column. Thus it will be seen that the arm not only swings freely around the column, but since it is capable of sliding through the sleeve 6, its radial length may be shortened during rotation. This important feature I utilize to 50 draw the bag in toward the post after its delivery by the passing train. For this purpose I mount upon the inner end of the arm 4, an antifriction roller 7 which bears against 55 the edge of the cam 3, so that as the arm ro-

tates and the roller 7 runs out on the cam the arm is drawn through the offset 5 on the sleeve 6, and its radial length during the continuance of its rotation is thus shortened so that the bag is carried in safety.

The tendency of the arm under the influence of centrifugal force to slide out again to its original position after the roller 7 has passed the outer face of the cam 3, is prevented by a suitable catch, such as the catch 8 pivoted on the offset 5. This catch drops below the stop 9 on the arm as the roller 7 moves outward on the cam and prevents the arm from sliding out again.

While any suitable device may be used in 70 connection with this arm for receiving and holding the bag as it is delivered by the passing train, I prefer that shown in the drawing which consists of a receiving hook 10 and a pivoted finger piece 11 mounted on the 75 arm 4 and provided with holding fingers 12 and 13 and an actuating finger 14. The impingement of the bag against the finger 14 swings the finger 13 toward the hook, against which it holds the bag during the revolution of the arm around the column.

It will be noted from the drawing that the finger piece 11 is subjected to the action of a spring 15 through the rod 16 pivoted to the lug 17, so that when the arm is set to receive 85 a bag, the retaining finger 13 is held open by the action of the spring which presses the finger 12 with its stop 18 against the back of the hook, while when the finger 13 is swung in by the impact of the bag against the finger 14, the spring now presses the latter against the bag and thus secures it within the hook. The spring 15 may be conveniently mounted on the rod 16 resting at one end against a swiveling abutment 19 carried by the arm 95 and at the other end against an adjustable abutment 20 on the rod.

In connection with this rod may also be provided a pivoted catch 21 carried by the arm and latching in a recess in the cam, by 100 which the arm is held in position when set to receive a bag. By a suitable connection with the rod 16 this catch is automatically lifted at the moment the bag strikes the finger 14 and thus the arm is freed for rotation.

A swinging arm 22 for delivering pouches 105 may be mounted on a crane above the receiving arm and the whole used for both catching and delivering pouches as shown in Fig. 1. To enable the receiving arm to be used on a 110

single track road the hook may be made to swivel in the arm and thus present its opening in either direction.

It will be readily seen from the above description that my device permits the free rotation of the bag after it is caught, thus saving the bag from injury and the apparatus from severe strain, while at the same time I avoid the dangers both to bag and train, which usually accompany a device which permits the bag to revolve, since I draw the bag at once away from the train and hold it at a safe distance while it spins around the supporting column.

While the apparatus which I have described is my present preferred construction and is especially adapted for receiving and delivering mail bags, various modifications may be devised by which the principles involved are applied without departing from the scope of my invention, and I do not limit myself to the particulars shown and described.

No claim is made herein to the broad idea of a rotatable catching arm provided with a catching device comprising a receiving hook, a retaining finger device pivoted on said arm, spring means to hold said device against the bag after it has been delivered and means for actuating said device by the impact of the bag on its delivery. This device in its broad aspect forming the subject of a divisional application filed March 14, 1908, and bearing the Serial Number 421,112, based upon the present application.

I claim as my invention:

1. A device of the character described, having a support, a freely rotatable catching arm mounted thereon and means for shortening the radial length of said arm during its rotation.

2. A device of the character described, having a support, a rotatable catching arm mounted thereon and means for shifting the axis of rotation of said catching arm during its rotation.

3. A device of the character described, having a support and a catching arm, in combination with a rotatable carrier for said arm slidably connected thereto and mounted on said support and cam means for sliding said arm with relation to its carrier during their rotation.

4. A device of the character described, having a support and a catching arm, in combination with a carrier for the latter mounted on the former and means for sliding said arm horizontally on its carrier.

5. A device of the character described, having a support, a cam thereon, a carrier freely rotating on said support, a catching arm slidably secured to said carrier and a bearing for said arm on said cam whereby the axis of rotation of said arm is shifted lengthwise thereof during its revolution, substantially as described.

6. A device of the character described, having a support, a rotatable catching arm mounted thereon and means for shifting the axis of rotation of said catching arm during its rotation, in combination with means to hold said arm after said axis of rotation has been shifted.

7. A device of the character described, having a rotatable catching arm, means for shortening the radial length of said arm during its rotation, and a catching device thereon comprising a receiving hook, a retaining finger device pivoted on said arm, spring means to hold said device against the bag after it has been delivered and means for actuating said device by the impact of the bag on its delivery.

8. A device of the character described having a rotatable arm provided with a catching device and a latch to hold said arm when set to receive a bag in combination with means for shifting the axis of rotation of said arm during its rotation.

9. A device of the character described having a rotatable arm provided with a catching device, a latch to hold said arm when set to receive a bag and means for automatically disengaging said catch by the impact of the bag on the catching device in combination with means for shifting the axis of rotation of said arm during its rotation.

10. A device of the character described having a rotatable arm provided with a catching device, comprising a retaining finger device actuated by the impact of the bag, in combination with a pivoted catch to hold said arm in position when set to receive a bag and a connection between said catch and retaining finger device whereby said catch is lifted upon the impact of the bag, substantially as described.

In testimony whereof I have signed my name to this specification, in the presence of two subscribing witnesses.

BENJAMIN LOUIS TOQUET.
